CLAIM

The ornamental design for an angle bar, as shown and described.

DESCRIPTION

FIG. 1 is a perspective view of an angle bar showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detail view of the portion 8 of FIG. 1; and,

FIG. 9 is an enlarged detail view of the portion 9 of FIG. 2. The broken lines in FIGS. 1, 2, 8, and 9 illustrate the border of enlarged detailed views and form no part of the claimed design.
